United States Patent Office

Des. 229,579

Patented Dec. 11, 1973

229,579

RADIO

Morris Fink, Great Neck, N.Y., assignor to Windsor
Industries, Inc., Plainview, N.Y.

Filed Dec. 11, 1972, Ser. No. 313,830

Term of patent 14 years

Int. Cl. D14—03

U.S. Cl. D56—4 B

FIG. 1

FIG. 2

FIG. 3

FIG. 4

FIG. 5

FIG. 6

FIG. 1 is a top plan view of a radio, showing my new design;

FIG. 2 is a left side, top and front perspective view;

FIG. 3 is a right side elevational view;

FIG. 4 is a rear elevational view;

FIG. 5 is a left side elevational view; and

FIG. 6 is a bottom plan view thereof.

Portions of FIG. 2 are stippled to indicate contrast in appearance.

I claim:

The ornamental design for a radio, as shown and described.
